DOOR CONTROL FOR ELECTRIC PULL SOCKETS

Andrew S. Kinney, Redwood Falls, Minn.

Application April 4, 1940, Serial No. 327,906

2 Claims. (Cl. 200—54)

This invention relates to a door control for electric pull sockets.

It is primarily aimed to provide such a device as will effect the lighting of a lamp when a door is opened, with the lamp remaining illuminated after the door is closed and which will cause extinction of the lamp when the door is again opened as in the act of leaving the room or location where the lamp is located. Such a device has particular use, where a lamp is to be illuminated upon approach into a room and while remaining in a room and is to be extinguished upon leaving such room. Examples of such a room are toilets, basements, garages, and attics.

The more specific objects and advantages will become apparent from a consideration of the description following taken in connection with the accompanying drawing illustrating an operative embodiment.

In said drawing:

Figure 1 is a fragmentary view in horizontal section through a room in connection with which my improvements are shown;

Figure 2 is a vertical sectional view taken on the line 2—2 of Figure 1;

Figure 3 is a horizontal section of a fragment of a room showing a modified form of my improvements, and

Figure 4 is a vertical section taken on the line 4—4 of Figure 3.

Referring specifically to the drawing and first to the form shown in Figure 2, a conventional room is suggested at 10 having a door 11, adapted to swing outwardly on a vertical axis 12. An electric lamp 13 is operatively wired within the room 10 and it is operated by a pull chain 14 and conventional switch mechanism, which lights and extinguishes the lamp 13 through alternate pulls on the chain 14.

A bracket 15 is suitably fastened as at 16 to wall structure within the room 10 and an angular control lever 17 is pivoted on a vertical axis at 18 to the bracket 15. A coil spring 19 is fastened to one arm of lever 17 and to the bracket 15 while another coil spring 20 is fastened to the other arm of the lever 17 and to an eyelet or the like 21 on the inside of the door 11. Such springs 19 and 20 maintain the angle lever 17 in the predetermined position shown by the full lines in the drawing.

A draw element in the form of a cord or the like 22 is fastened to one end of one of the arms of lever 17 and at the other end to the pull chain 14, such draw element being guided over a pulley 23 pivoted at 24 on the bracket 15.

Presuming lamp 13 to be extinct, upon door 11 being opened by pulling outwardly thereon, the parts will be moved from the full line to the dotted line position in Figure 1, spring 20 being tensioned and rocking the lever 17, tensioning

the spring 19, pulling the draw member 22 and the pull chain 14, thereby causing lamp 13 to illuminate. Upon the door 11 being closed, the springs 19 and 20 restore the lever 17 to its normal position and providing sufficient slack in the draw element 22 to enable the pull chain 14 to return to its original position for a succeeding operation. It will be realized, that the interior of the room 10 will thus be lighted and has been lighted through the act of the person opening door 11 and entering the room. Upon such person leaving the room, he will open the door 11, thus again moving the parts to the dotted line position and pulling the chain 14, so that upon closing the door 11, the lamp 13 will be extinguished and the chain 14 moved to position for the succeeding operation.

In Figures 3 and 4, the invention has been shown in connection with a door 11' which is adapted to swing inwardly in opening it, from a vertical axis at 12'. In connection with such a structure, the bracket 15 is fastened onto the doorframe as shown. In addition, a bracket 25 is fastened as at 26 to the door 11' and the spring 20 instead of being fastened to the eyelet 21 is fastened to said bracket 25. Otherwise, the structure corresponds to that of the first form and operates in the same manner and performs the same function as the first form of the invention through the opening and closing of the door 11'.

Various changes may be resorted to provided they fall within the spirit and scope of the invention.

I claim as my invention:

1. A door operable control for an electric pull socket comprising a mounting bracket, a lever pivoted to said bracket, a spring connected to the lever and to the bracket, a spring connected to the lever on the other side of the pivot from the first mentioned spring and adapted for connection to the door, a draw means extending from the lever for connection to the electric pull socket, a guide means over which the draw member passes, said guide means being mounted by said bracket, said lever being of L-shape, and the bracket having an arm to which the lever is pivoted.

2. In combination, a closure, and L-shaped bracket secured by its face portion to a supporting structure, a bell-crank pivotally secured at its heel portion to the outstanding portion of the L-shaped bracket, a tension spring between an intermediate portion of one leg of the bell-crank and the heel portion of the L-shaped bracket, a switch, a connection between one end of the bell-crank and the switch and a connection between the other end of the bell-crank and the closure.
